UNITED STATES PATENT OFFICE.

LLOYD B. JONES, OF TOLEDO, OHIO.

CAR-DUMPING MACHINE.

1.180,298.

Specification of Letters Patent. Patented Apr. 25, 1916.

Application filed April 4, 1914. Serial No. 829,484.

To all whom it may concern:

Be it known that I, LLOYD B. JONES, a citizen of the United States, residing at Toledo, in the county of Lucas and State of Ohio, have invented certain new and useful Improvements in Car-Dumping Machines, of which the following is a specification.

The invention relates to machines for dumping cars, and more particularly to that class of machines used in loading boats, wherein a standard coal or ore car is raised above a distributing receptacle and the contents of the car dumped therein by tilting the car. The invention has for its primary objects, the provision of an improved car handling mechanism wherein cars are elevated and dumped with great facility; the provision of means whereby a plurality of cars are handled at the same time, thereby saving considerable time in the process of dumping a car and returning it to the car yard; the provision of means whereby cars are received from the yard and returned thereto with a minimum manipulation and a great saving of time; the provision of improved means for distributing the material into the boats wherein there is considerable saving of time, and such other improvements as will hereinafter appear. One embodiment of the invention is shown in the accompanying drawings, wherein—

Fig. 1 is a side elevation of the car dumping machine, showing a boat in position for receiving material dumped from the cars; Fig. 2 is a rear elevation of the car dumping machine; Fig. 3 is an end elevation of a cradle for the cars; Fig. 4 is an enlarged front elevation of the apron and the discharge chute or tube, showing the boat in section; Fig. 5 is a diagrammatic drawing showing the movement of the cradle during the dumping cycle of its movement, Fig. 6 is a diagrammatic front elevation of the machine showing its relative position with the car yard, the dock and the boat, and Fig. 7 is an end view of a cradle showing a pawl mechanism for supporting the cradle independently of the carrier.

Referring to Figs. 1 and 2, the general parts of the machine may be designated by numerals wherein, 1 is a structural frame which carries and supports the car dumping machine, 2 is a rotary cradle carrier for moving the cradles into operative positions,

3, 4, 5 and 6 are cradles suspended between the cradle carrier wheels 2 in which the cars 7 are securely clamped, 8 is a crane carrying the hoists whereby the cradles are elevated and turned over to dump the cars, 9 is an apron into which the material is dumped 60 from the car, 10 is a discharge tube or distributor for the material, and 11 is a boat into which the distributor discharges the material dumped from the cars.

The cradle carrier wheels 2 are supported 65 by the rollers 12 mounted on the foundation block 13 and by the rollers 14 mounted upon the frame 1. The rollers 12 and 14 engage the wheels 2 in the grooves 15 in the rims of the wheels which serve as a guide to keep 70 the wheels 2 in proper position, and the wheels 2 are further retained in position by the axles 16, Figs. 1 and 2. The axle 16 merely serves as a positioning member, as the weight of the wheels and their load is 75 carried entirely by the rollers 12 and 14.

The cradles 3, 4, 5, and 6 are suspended between the carrier wheels 2 and are supported on such carriers by means of the pins 17 secured to the cradles resting in the 80 sockets 18 in the depending ends of the hangers 19 pivoted to the carrier wheels 2 at 20. The pins 17 are secured to the upper portion of the ends of the cradles, and as the center of gravity of the cradles is at all 85 times below the pins or the point of support of the cradles, the cradles will always assume the upright position when supported in the carrier wheels 2.

The hangers 19 turn freely on the pivots 90 20, and as the sockets 18 are at the opposite end of the hanger relative to the pivots they will always assume the vertical position as shown in Fig. 1, regardless of whether a cradle is resting in the sockets or not. The 95 purpose of the hangers is to provide a socket into which the cradle pins may be lowered and which will support these cradles regardless of the position of the carrier wheel. When a cradle is lifted from the sockets 100 they will not change their position, but will remain in proper position to receive the pins of the cradle when the cradle is lowered so that the pins may engage the sockets.

The cradles (Figs. 1, 2, and 3) consist of 105 two solid circular end portions 21 connected by a structural frame portion 22 (Figs. 2 and 3) end portions being provided with openings

23 through which a car may pass into the structural portion where it is clamped by any suitable means, such as by adjustable blocks 24 (Fig. 1). The ends 21 of the cradle are supported, when out of the sockets 18, by means of sprocket chains 26 which surround the grooves 25 in the ends 21, these chains being in turn supported over a sprocket wheel 27.

10 The two sprockets 27 are connected by the shaft 28 (Figs. 2 and 3) which extends through two combined support and motor housings 29, the shaft 28 being driven by a motor 30 within each housing 29, through 15 the spur gear pinions 31 and the spur gears 32. Normally the housings 29 are supported upon the gear shrouds 33 on the cradle ends 21, by means of the outwardly extending lugs 34 (Figs. 2 and 3), the lugs 34 also 20 serving to prevent rotation of the housings 29 about the axis 28 when the motors are started for the purpose of rotating the cradles. Each housing 29 is provided at its top with a transverse slot 35 having enlarged openings 36 and 37 at the ends of the slot for the admission and exit respectively, of a T-hook 38 through the openings at the topmost part of the housing 29, and adjacent the transverse slot 35, sockets 39 are 25 provided to engage the ends of the T-hook 38 when the hook is raised after it has entered the slotted opening 36. The manner of operating the hook and the purpose of this peculiar slot and socket construction 30 will be described later.

In the machine disclosed in the drawings, there are four cradles, 3, 4, 5, and 6 employed, but it is quite obvious that a greater or less number may be used to advantage, 40 four cradles being shown for the purpose of illustrating this particular machine. The four cradles are suspended between the carrier wheels 2, from the pivots 20 which are equidistant from the center of the carrier wheels 2, and spaced equidistantly about the circumference of the wheel, and in this machine there are four operative stations for the cradles, viz., station A where a car 7 is loaded upon a cradle, station B where 45 a cradle is lifted from the carrier to be subsequently turned over and the contents of a car dumped therefrom, station C where a car is discharged from the cradle by means of some suitable ram mechanism (not shown) carried by frame 1, and station D where a car may either be loaded onto a cradle or discharged therefrom, according to which operation is found to be the most desirable. There are some conditions where- 50 in it might be desirable to alternately load a car at station A and station D.

The cradle carrier wheels 2 are intermittently turned clockwise, thus causing the cradles 3, 4, 5, and 6 to consecutively register with a particular station, and each

cradle will pass successively the stations A, B, C, and D when the carrier wheels 2 have made a complete revolution. The carrier wheels 2 are mounted independently upon the frame 1 and roller bearings 12 and 14, 70 but are driven synchronously by means of chains 40. (Figs. 1 and 2) which are meshed with the sprockets 41 keyed to the same shaft 42. Shaft 42 is driven by the motors 43 through motor pinions 44, spur gears 45, 75 shaft 46, pinions 47 and spur gears 48.

Shaft 42 is supported in bearings 49 carried by the frame 1, and carries at each end in addition to the sprocket 41, a brake drum 50 (Figs. 1 and 2) provided with a brake band 51 operated by one electric solenoid or some other suitable operating means. The purpose of this brake mechanism is to gradually stop the rotation of the carrier wheels 2 when the cradles are alined with 80 the operative stations, and to hold the wheel 2 stationary until it is desired to again advance the cradle to the next station.

The crane 8 is mounted on the top of the frame 1 and carries a hoist for elevating 85 the cradles into final dumping position, cradle 6 (Fig. 1) being shown in such position. Normally the crane 8 and the T-hooks 38 carried by the hoist are in the position shown in Fig. 2, and shown in dotted lines in Fig. 1, the hooks being connected by a rod or bar 38A, and as a cradle is brought up from station A, and when almost in operative position with station B, the T-hooks 38 which are hanging in their lowermost 90 position enter the openings 36 in the housings 29. When the cradles have stopped moving the hoist motors 52 (Fig. 2) are started, causing the T-hooks to rise through the following media: the motor 52 drives the shaft 53 (Fig. 2) through the spur pinion and gear 54 and 55 respectively, the shaft 53 turns pinions 56 which mesh with gears 57 secured to the cable drums 58. Drums 58 wind up cables 59 which pass over sheaves 60 and thence to double sheave blocks 61 attached to T-hook 38, and finally around double sheave blocks 62 mounted on the crane 8.

Between the sheave blocks 62 and 61 are mounted on the underside of the crane two stops 63 (Fig. 1) which engage sheave blocks 61 when they have been raised a sufficient distance. When the hoist motors are started the cradle is lifted from the station B until the tilting pin 64 at each end of the cradle (Figs. 1 and 3) engage stops 63 mounted on the frame 1, at which time the cradle will start to rotate about its center and its center will swing about the pins 64 as a center of revolution until the second pins 66 at each end of the cradle engage the stops 65 at 77 (Fig. 3). Further raising of the cradle will cause the cradle to further rotate about its center and its center will

revolve about pins 66 as a center of revolution until pins 64 have been disengaged from the stops 65, at which time the cradle is free to rise vertically.

5 Before the cradle has been elevated sufficiently to disengage pins 64 from stops 65, the sheave blocks 61 (Fig. 1) engage the stops 63 on the crane, which results in the crane 8 being pulled up the incline on the 10 frame 1, toward the left, thus bringing the cradle into the position shown at E in Fig. 1. Just prior to the assuming of this position by the cradle the tilting pins 64 were disengaged from the stops 65 and the car 15 already was dumping its contents into the apron 9. Further winding up of the cables 59 upon the drums 58 draws the crane farther to the left, the cradle being moved into the position shown in dotted lines at F (Fig. 5)-the pins 64 and 66 having caused the 20 cradle to rotate counter-clockwise by reason of their engagement with the upwardly extending wing of the stop 65. The line of travel of the center of the cradle from the 25 time the pins 64 engaged the stop 65 until the cradle assumes its highest position as shown by position of cradle 6 in Fig. 1 and position G in Fig. 5, is designated by the heavy dotted line H.

30 It has been found that when a car is tilted into the position E (Fig. 1) a portion of the material remains in the corner I (see cradle 6, Fig. 1), and to dislodge such material it was found that by turning the car 35 over into the position of cradle 6 such material would fall out without repeated rocking of the car or cradle. The cradle is tilted to position F (Fig. 5) by the pins 64 and 66, and to turn the car into the position of cradle 6, the motors 30 in the housings 29 40 are started, which causes the cradle to rotate.

The instant all material is dumped from the car, the hoist motors 52 are reversed, 45 causing the crane to descend into normal position, and at the same time the cradle is being rotated by the cradle motors, in the direction of the arrow, until the cradle has resumed its initial vertical position. The 50 speeds of the motors 30 are so regulated that the supporting pins 17 carried by the cradles are in the proper position to descend into their respective sockets 18 when the hoist has sufficiently lowered the cradle for 55 them to do so. Steps 67 are mounted upon the frame 1 to stop the descent of the crane at the proper place.

When a cradle has been deposited upon the carrier wheels 2, the wheels are immediately started to rotate and the upward movement of the cradle in its orbit causes the T-hooks to slide out of the housings 29 through the openings 37 formed in the housing for that purpose. Thus the hoist hooks 38 are automatically disengaged from the cradle and the hooks remain in position to

automatically engage the succeeding cradle. Instead of a T-hook a ball hook may be substituted, which would have the advantage of being always in proper position to enter the openings in the housing and engage the 70 sockets therein.

To prevent rocking of the cradles when they are in operative position, a series of properly positioned guides 68 mounted on frame 1 (Figs. 1 and 2) engage the pins 64, 75 66 and 69 on the ends of the cradles in such manner as to prevent the cradles from swinging about the pivot pins 20. The guides 68, however, do not interfere with the movement of the cradles in their orbit. While the guides 68 are shown only at the stations A and D, by the adaptation of a suitable support for them they may be employed at the stations B and C.

Pivoted to the guides 68 at station A (Fig. 7) are a pair of weighted pawls 68^a which engage the pins 64 and 66 when the pins pass to the left over the guides 68, and which serve to support the cradles when a cradle arrives at the station A where a car is loaded onto the cradle. The pins 64 and 69 engage the side faces of the pawls and press them downward when passing over them, and when they have assumed the position shown in Fig. 7, the counterweights on the pawls cause the pawls to again assume normal position and hold the cradle against downward movement toward the right. When a cradle is brought to station A the carrier wheel 2 is allowed to settle or back up sufficient to cause the cradles to rest upon the guides 68 and the pawls 68^a, thereby relieving the carrier wheels of any shock when a car is loaded upon the cradle.

Referring to Figs. 1 and 4, the boat loading apparatus will be considered. The contents of the cars is dumped into an apron or receptacle 9 which is pivoted at 70 (Fig. 1) so that it may be raised by a suitable hoisting cable 71 to clear masts, stacks, etc., projecting upwardly from the boat, when the boat is being positioned. This apron is preferably made of sufficient size to hold five or six car loads of material, so that the 105 operation of the dumping machine will be more or less continuous while a boat is being loaded, in case the discharge from the apron is momentarily interrupted. The bottom of the apron has converging walls 110 which slope to a discharge opening 72 which is closed by a hinged gate 73 controlled by the operator located in the cabin 74 carried by the apron frame 75.

Beneath the discharge opening of the 115 apron is suspended from the pivot 76 a distributing chute or "trimmer" made of sections of tubing which are adapted to telescope one into the other in order to contract the chute as the material rises in the boat. The section 77 of the trimmer is pivoted

at 78 in a direction transverse to the pivot 76, thereby providing a universal joint near the top of the trimmer, permitting the lower end of the trimmer to be moved in all directions as desired.

- When it is desired to discharge material into the boat, the operator lowers the trimmer to its full extent, by means of the cable 79 secured at one end to the bottom of the 10 apron and passing under the sheave 80 carried by the trimmer, to a drum 81 controlled by the operator. The gate 73 is then opened and a quantity of material dropped into the boat, such material being leveled or 15 trimmed by causing the trimmer to be swung transversely of the boat, or longitudinally thereof, as may be required, over the surface of the material, thus scraping it into proper position.
- 20 The trimmer is swung transversely of the boat by the cable 82 (Figs. 1 and 4) secured to the trimmer opposite the sheaves 80, and which passes over the sheaves 83 (Fig. 4) and 84 (Fig. 1) on the apron frame 75. 25 the ends of cable 82 being wound upon suitable winding mechanism controlled by the operator. Longitudinal swinging of the trimmer is caused by a similar mechanism operating the cable 85 (Figs. 1 and 4) secured to the bottom section of the trimmer and passing over the sheaves 86 and 87 carried by the apron frame 75.

- When a bulkhead or compartment of the boat is filled, the trimmer is telescoped and 30 swung longitudinally and transversely so that it may clear the partition, as shown in dotted lines in Fig. 4, and discharges into the next compartment without shutting off the discharge of material or waiting until 35 the boat is shifted to a new position, thus saving considerable time in the manipulation of the discharging apparatus. Heretofore it has been necessary to telescope the trimmer and stop dumping the car until the 40 boat was moved to a new position, thus losing valuable time while the boat was being shifted. This delay was occasioned by the 45 inability to swing the trimmer longitudinally of the boat and inability to stop the 50 flow of material from the apron.

- A general arrangement of the car dumping machine, the boat, and the tracks for the cars, is shown in Fig. 6 wherein C' is an inclined track leading from the station C of 55 the machine to the car yard J, and is for the purpose of returning empty cars to the yard, and A' is an inclined track leading from the yard J to station A of the machine. An additional track D' indicated in Fig. 2 60 and not visible in Fig. 6, runs parallel to the track A' and connects the yard J with station D on the machine.

- The operation of the machine is as follows. Cars are run down either the track 65 A' or the track (not shown) leading to sta-

tion D, and assuming that a car has been run down track A', it will be loaded onto the cradle 3 by the force of gravity and securely blocked therein. At the same time a car on cradle 5 is shoved off the cradle onto track 70 C' and it returns to the yard J by the force of gravity.

After a car has been loaded on cradle 3 and a car removed from cradle 5, the carrier wheel motors 43 are started and the carrier 75 turns clockwise until cradle 3 registers at station B. The electric brake is then set and the cradle carrier held stationary while a car is loaded onto cradle 4 from track A' and an empty car removed from cradle 6 80 onto track C', and while cradle 3 is being elevated, dumped and replaced on the hangars 19 at station B.

When cradle 3 is moved into operative position at station B the cradle automatically engages the hoist T-hook, and when the cradle carrier comes to rest, the hoist motors 52 are started, causing the cradle 3 to be raised from the socket hangers 19. Immediately after the pins 17 are free from the 90 sockets 18 in the hangers 19, the pins 64 engage the stops 65 and the cradle is tilted as it is elevated, in the manner previously described. When the sheave blocks 61 engage the stops 63 on the crane the crane is 95 pulled to the left by cables 59 carrying the cradle out over the apron 9 where it is caused to be rotated a complete revolution, dumping its contents into the apron 9.

After all material is dumped from the car 100 in cradle 3 the hoist motors are reversed, causing the crane to return to normal position, and the hoist to lower the cradle onto the hangers 19, carried by the cradle carrier. When the cradle is received by the carrier, 105 the electric brake is released and the carrier motors are again started to rotate the cradle carrier clockwise so as to register cradle 4 with the dumping station B.

The first movement of cradle 3 in its orbit 110 automatically releases the hoist hook from the cradle, in the manner previously described, and the hook is then left in position to automatically engage cradle 4 when it is brought into position. Upon the arrival of 115 a new cradle at the dumping station, the operation just described is repeated, and a full car is loaded onto the machine at station A and an empty car discharged at station C, and so on, all the operations being repeated. 120 Material received in the apron is distributed to the boats in the manner previously described.

What I claim is:

1. In combination in a car dumping machine having a plurality of operative stations for the cars, a rotary carrier provided with a horizontal axis and cradles for the cars pivotally suspended from the carrier and adapted to be maintained in upright po- 125

- position as the carrier rotates, and means for moving the cradles into operative position with the stations.
2. In combination in a car dumping machine having a plurality of operative stations for the cars, a rotary carrier provided with a horizontal axis and cradles for the cars pivotally suspended from the carrier and adapted to be maintained in upright position as the carrier rotates, and means for dumping the cars when they have moved to a predetermined position.
3. The combination with a car dumping machine having a Perris wheel carrier frame, cradles for the cars pivotally suspended within the frame, of means for dumping a car when it has been elevated a predetermined distance.
4. In a car dumping machine, a rotary carrier for successively elevating cars into dumping position, means for detaching the car from the carrier when elevated, and means independent of the carrier for dumping the cars after they are detached.
5. In a car dumping machine, a cradle for a car, a carrier for the cradles to which the cradles are detachably secured, means for moving the cradle into operative dumping position, and means for detaching the cradle from the carrier before the car is dumped.
6. In combination in a car dumping machine having a dumping station, a series of cradles for the cars, a rotary carrier for the cradles to which the cradles are detachably suspended, means for moving the cradles into operative position with the dumping station, means for detaching a cradle from the carrier, and means for rotating the carrier to dump the car after the cradle has been removed from the carrier.
7. In combination in a car dumping machine having a dumping station, a series of cradles for the cars, a rotary carrier for the cradles to which the cradles are detachably suspended, means for moving the cradles into operative position with the dumping station, a hoist for detaching a cradle from the carrier, and means for automatically attaching the hoist to the cradle when the cradle is brought into operative position with the dumping station.
8. In combination in a car dumping machine having a dumping station, a series of cradles for the cars, a rotary carrier for the cradles to which the cradles are detachably suspended, means for moving the cradles into operative position with the dumping station, a hoist for detaching a cradle from the carrier, and means operating with the hoist for rotating the cradle when the cradle is raised from the carrier.
9. In combination in a car dumping machine, a rotary cradle carrier, a detachable cradle for a car adapted to maintain a vertical position during the rotation of the car-
- ries, and a socket open at the top carried by the carrier for supporting the cradle, from which the cradle may be removed and replaced by vertical movement, and means whereby such opening in the socket is maintained in upper position throughout the revolution of the carrier.
10. In combination in a car dumping machine having a plurality of operative stations, a pair of independently mounted rotary carriers spaced apart, a series of cradles for the cars pivotally suspended between the carriers, and means whereby the carriers are moved synchronously to bring the cradles into operative positions with the stations.
11. In combination in a car dumping machine having a plurality of operative stations for the cars, a cradle carrier, a series of cradles for the cars pivoted to the carrier at a point above the center of gravity of the cradles, means for intermittently rotating the cradle carrier whereby the cradles are brought into operative positions with the stations, and guide means for preventing rocking of the cradles when the said cradles are in operative position.
12. In combination in a car dumping machine, a frame, a hoist supported by the said frame, a cradle for a car adapted to be raised by the hoist into dumping position, a pair of tilting pins on the cradle, a stop carried by the frame adapted to engage one of the pins upon upward movement of the cradle and to cause the cradle to tilt about the first pin as a center until it engages the other pin, whereafter the cradle turns about a new center and disengages the first pin from the stop, permitting further unobstructed vertical movement of the cradle.
13. In combination in a car dumping machine, a cradle for a car, a hoist for elevating the cradle to dumping position, and means operated by the movement of the cradle for disengaging the hoist from the cradle.
14. In a car dumping machine, the combination with a hoist adapted to receive and discharge a car at the same location, of a rotary means for laterally displacing a car from such receiving and discharging position after a car has been released from the hoist.
15. In combination in a car dumping machine having a plurality of operative stations, a pair of independently mounted rotary carriers spaced apart, a series of cradles for the cars pivotally supported by the carriers, and means whereby the carriers are moved synchronously to bring the cradles into operative positions with the stations.
16. In combination in a car dumping machine having a plurality of operative stations for the cars, a cradle carrier, a series of cradles for the cars pivoted to the cradles at a point above the center of gravity of

the cradles, means for intermittently rotating the cradle carrier whereby the cradles are brought into operative positions with the stations, and means engaging the cradles for holding the cradles in operative position.

17. In a car dumping machine, a cradle for the car, a hoist for elevating the cradle into dumping position, tilting means engaging the cradle and coacting with the hoist for tilting the cradle as the cradle is raised, and means coacting with the hoist for disengaging the tilting means.

18. In a car dumping machine, a cradle for the car, a hoist for elevating the cradle into dumping position, tilting means engaging the cradle and coacting with the hoist for tilting the cradle as the cradle is raised, and means coacting with the hoist for disengaging the tilting means when the cradle has been tilted a predetermined distance.

19. In combination in a car dumping machine, a cradle adapted to receive a car, a rotary carrier for the cradle adapted to

move the cradles from car receiving position to car dumping position, and means whereby the cradle is supported independently of the carrier when a car is received by the cradle.

20. In combination in a car dumping machine, a cradle adapted to receive a car, a rotary carrier for the cradle, and means whereby the cradle is supported independently of the carrier when a car is received by the cradle.

21. In combination in a car dumping machine, a cradle adapted to receive a car, a rotary carrier for the cradle, and means whereby the cradle is supported independently of the carrier when a car is being dumped.

In testimony whereof I have hereunto signed my name in the presence of the two subscribed witnesses.

LLOYD B. JONES.
